UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 24, 1923. Serial No. 659,103.

My invention relates to railway traffic controlling apparatus, and particularly to apparatus of the type comprising means for supplying train governing energy to the trackway, and train-carried governing means controlled by such energy.

More specifically, the present invention relates to the trackway portion of such apparatus.

10 I will describe one form of apparatus embodying my invention, and will then point out the novel features thereof in claims.

15 In the accompanying drawings Fig. 1 (right and left hand sheets) is a diagrammatic view showing one form of apparatus embodying my invention.

20 Referring to the drawings, the reference characters 1 and 1^a designate the track rails of a railway track A over which traffic moves in both directions. These rails are divided by insulated joints 7 to form a plurality of track sections, of which only four sections 2-3, 3-4, 4-5 and 5-6, are shown in the drawing.

25 Each track section is provided with a track circuit, comprising a battery 8 connected across the rails adjacent one end of the section, and a track relay connected across the rails adjacent the other end and 30 designated by the reference character T with a distinguishing exponent. In series with each battery 8 is the secondary of a transformer J, the purpose of which will be set forth hereinafter.

35 Westbound traffic along the track A is governed by signals S⁵ and S², whereas eastbound traffic along the track is governed by signals S³ and S⁴. Each of these signals is adapted to give three different indications, 40 such as "Proceed", "Caution" and "Stop", and, as here shown, each signal is of the single arm three position semaphore type.

45 Each signal is immediately controlled by a line relay designated by the reference character H with the same exponent as that applied to the signal. Each of these relays is of the polarized type, so that it is responsive to reversals of the polarity of the current by which it is energized. Referring 50 particularly to signal S⁵, this signal is provided with a caution circuit which passes from battery B⁵, through wire 9, contact 10 of relay H⁵, wire 11, operating mechanism of signal S⁵, wire 12, contact 13 of relay H⁵

and wires 14 and 15 to battery B⁵. This signal is also provided with a proceed circuit which passes from battery B⁵, through wire 9, contact 10, wire 16, polar contact 17 of relay H⁵, wire 18, operating mechanism of signal S⁵, wire 12, contact 13, and wires 14 and 15 to battery B⁵. When relay H⁵ is energized by current of what I will term "normal" polarity, the polar contact 17 is closed, so that signal S⁵ indicates proceed. When relay H⁵ is energized with current of what I will term "reverse" polarity, contact 17 is open so that signal S⁵ then indicates caution. When relay H⁵ is deenergized, its neutral contacts 10 and 13 are open, so that signal S⁵ then indicates stop.

70 Each of the remaining signals S², S³ and S⁴, is controlled in a similar manner by its associated line relay E, the proceed and caution circuits of these signals being omitted from the drawing, however, for the purpose of simplicity.

75 Line relay H⁵ for signal S⁵ is provided with a line circuit which passes from battery B², through pole changer P², wire 19, contact 20 of track relay T², wire 21, contact 22 of track relay T², wires 23 and 24, contact 25 of track relay T², wire 26, winding of relay H⁵, wires 27, 28 and 29, common wire O, wires 30, 31 and 32, and pole changer P² to battery B². Pole changer P² is operated 80 by signal S² in such manner that when signal S² indicates proceed or caution, current of normal polarity is supplied to relay H⁵, so that signal S⁵ then indicates proceed; when, however, signal S² indicates stop, current 85 of reverse polarity is supplied to relay H⁵, so that signal S⁵ then indicates caution. Of course, if any one of the track relays T², T³ or T⁴ is open, the circuit just traced for relay H⁵ is open, so that this relay is de- 90 energized and signal S⁵ indicates stop.

95 Signal S² is controlled by relay H², which in turn is controlled by traffic conditions to the west of this signal through the medium of suitable apparatus which may, for example, be similar to the apparatus for the control of line relay H⁵ explained hereinbefore. Line relay H³ for eastbound signal S³ is provided with a line circuit which passes from battery B⁴ through pole changer P⁴, wire 33, contact 34 of track relay T³, wire 35, contact 36 of a relay C⁴, wire 37, contact 38 of track relay T², wire 100

39, winding of relay H^s , wires 40, 31 and 30, common wire O, wire 41 and pole changer P^s to battery B^s . Pole changer P^s is operated by a signal S^s , and in so far as this pole 5 changer is concerned, the control of signal S^s is the same as the control of signal S^5 explained hereinbefore. It will be noted, however, that the circuit for relay H^s includes a contact 36 of relay C^4 , so that signal 10 S^s will indicate stop whenever relay C^4 is de-energized.

Relay C^4 is provided with a circuit which passes from battery B^s , through pole changer P^s , wire 44, contact 45 of track relay T^s , wire 46, contact 47 of track relay T^s , wire 48, winding of relay C^4 , wires 49 and 41, common wire O and wires 29, 28 and 50 and pole changer P^s to battery B^s . It will be seen, therefore, that relay C^4 will be de-energized whenever track relay T^s or T^s is open, that is, whenever there is a train in section 4—5 or section 5—6. In other words, the line circuit for relay H^s is directly controlled by the track relays for sections 2—3 and 3—4, and is indirectly controlled through the medium of relay C^4 by the track relays for sections 4—5 and 5—6, so that signal S^s indicates stop whenever there is a train between the points 2 and 6. 30 The line relay H^s for signal S^s is controlled by a circuit which is similar to the circuit hereinbefore traced for line relay H^s . That is to say, relay H^s is controlled by contact 42 of track relay T^s , contact 43 35 of relay T^s , and by other apparatus to the east of the stretch of track shown in the drawing.

Relay C^5 , corresponding to relay C^4 , is controlled in the same manner as relay C^4 , 40 in that the circuit for relay C^5 includes contact 52 of track relay T^s and contact 51 of track relay T^s , so that the westbound signal, located to the east of point 6, and corresponding to eastbound signal S^s , is held in 45 the stop position by a train between point 3 and the signal in question.

The operation of the apparatus thus far described is as follows:

As a westbound train approaches the 50 stretch of track shown in the drawing, it will first place signal S^s at stop by operating the track relays to the east of point 6. As the train passes point 6 it will open track relay T^s , thereby opening at contact 55 the circuit for relay C^4 , and the consequent opening of contact 36 of relay C^4 will open the circuit for line relay H^s , thereby placing signal S^s at stop. As the train passes signal S^s , it will place this signal at 60 stop by opening track relay T^s and thereby opening the circuit for line relay H^s at contact 25. As the train passes point 3 it will allow relay C^5 to close, and as the train passes signal S^s it will place this signal at 65 stop, so that signal S^s will return to the cau-

tion position. When the train reaches such point to the west of signal S^s that this signal moves to the caution position, signal S^s will return to the proceed position.

An eastbound train passing through this 70 stretch of track places signal S^s at stop as soon as it passes this signal, and it simultaneously will place signal S^s at stop. When the train passes signal S^s , this signal will, likewise, move to the stop position, 75 while signal S^s will remain in the stop position until the train passes point 6, that is, until relay C^4 is allowed to close.

The apparatus thus far described constitutes what may be termed a signaling system in that it relates only to the control of the wayside signals S. In addition to this apparatus I have provided means for supplying train governing energy to the track rails, such energy comprising an alternating track circuit current connected across the rails, and alternating line current connected to flow through the two rails in parallel. I will now proceed to explain the means for supplying such energy to the track. 80 85 90

Train governing energy is furnished by a generator F, which, as here shown, is of the three-phase type, the terminals being connected with wires 62, 63 and 64, respectively, 95 of a transmission line M.

Located adjacent signal S^s is a relay E^s , the circuit for which passes from battery B^s , through wire 58, winding of relay E^s , wire 59, contact 60 of line relay H^s , and wire 61 to battery B^s . Relay E^s controls the supply of current to the primary of a transformer J^s , the circuit for which primary passes from the secondary of a transformer G^s , through wires 65 and 66, contact 67 of relay E^s , wire 68, back point of contact 69 105 of track relay T^s , wire 70, contact 71 of relay E^s , wire 72, primary of transformer J^s , wires 73 and 74, contact 75 of relay E^s , and wires 76 and 77 to the secondary of transformer G^s . The primary of transformer G^s is connected across wires 63 and 64 of the transmission line M. The secondary of transformer J^s is connected across the rails of track section 2—3 at the west end of this section. It follows that when relay H^s is 110 energized and track relay T^s is de-energized, alternating current of what I will term "normal relative polarity" is connected across the rails of section 2—3. This current constitutes the track circuit current of the train governing energy system. When line relay H^s is de-energized, so that relay E^s is, likewise, de-energized, the supply of energy to the primary of transformer J^s is 115 discontinued at contact 71 of relay E^s . 120

Track circuit train governing energy is supplied to the west end of section 3—4 by a transformer J^4 , the secondary of which is connected across the rails of this section in series with the track battery 8. The circuit 125

- for the primary of transformer J^4 is from the secondary of transformer G^3 , through wires 65 and 66, contact 67 of relay E^2 , wire 68, front point of contact 69 of track relay T^2 , wire 80, primary of transformer J^4 , wires 81 and 82, common wire O , wires 30, 83 and 74, contact 75 of relay E^2 , and wires 76 and 77 to the secondary of transformer G^3 . This circuit does not include contact 71 of relay E^2 , and so the instantaneous relative polarity of the current supplied to transformer J^4 will depend on whether relay E^2 is energized or de-energized, it being noted that the contacts 67 and 75 of this relay constitute a pole changer. This pole changing may be accomplished in other ways if desired, such for example, as by a pole changer operated mechanically by signal S^2 . When relay E^2 is energized, current of what I will term "normal relative polarity" is supplied to the rails of section 3-4, whereas when relay E^2 is de-energized, current of what I will term "reverse relative polarity" is supplied to the rails of section 3-4.
- The supply of track circuit train governing energy to the east end of section 3-4 is accomplished by a transformer J^5 , the primary of which is controlled by a relay E^4 , which relay in turn is controlled by line relay H^4 for signal S^4 . When line relay H^4 is energized, relay E^4 is, likewise, energized, and the circuit for the primary of transformer J^5 then passes from the secondary of transformer G^4 , through contact 84 of relay E^4 , contact 85 of relay C^4 , back point of contact 86 of track relay T^3 , contact 87 of relay E^4 , primary of transformer J^5 , contact 88 of relay E^4 and wire 98 to the secondary of transformer G^4 . Track circuit train governing energy is supplied to the east end of section 2-3 by a transformer J^6 , the circuit for the primary of which passes from the secondary of transformer G^4 , through contact 84 of relay E^4 , contact 85 of relay C^4 , front point of contact 86 of track relay T^3 , primary of transformer J^6 , common wire O , and contact 88 of relay E^4 to the secondary of transformer G^4 . The instantaneous relative polarity of the current in this circuit is controlled by relay E^4 , and so by line relay H^4 for signal S^4 . In a similar manner current is supplied to the west end of track section 5-6 by a transformer J^9 , the primary circuit for which is controlled by a relay E^5 , and which relay is in turn controlled by line relay H^5 . Relay E^5 also controls the supply of track circuit train governing current to the primary of a transformer J^{11} , the secondary of which supplies such current to the west end of the section immediately to the east of point 6. The supply of track circuit train governing current to the east end of section 5-6 is furnished by a transformer J^{12} , the primary circuit for which is controlled by apparatus to

the east of point 6, and, consequently, not shown in the drawing.

The supply of track circuit train governing current to section 4-5 is controlled by two polarized relays D^4 and D^5 , each of which is normally de-energized. Relay D^4 is controlled by contact 54 of relay C^4 , the circuit for relay D^4 being from battery B^2 , through pole changer P^2 , wire 19, contact 20 of track relay T^2 , wire 21, contact 22 of track relay T^3 , wires 23 and 53, contact 54 of relay C^4 , wire 55, winding of relay D^4 , wires 56 and 41, common wire O , wires 30, 31 and 32, and pole changer P^2 to battery B^2 . It will be seen, therefore, that when relay C^4 is de-energized, relay D^4 is connected in the circuit of line relay H^5 in multiple with the latter relay, so that relay D^4 is then controlled in the same manner as relay H^5 , in so far as concerns the polarity of the current supplied thereto. That is to say, relay D^4 will be energized by current of normal polarity when signal S^2 indicates proceed or caution, and by current of reverse polarity when signal S^2 indicates stop.

When relay D^4 is energized in normal direction, current is supplied to the primary of transformer J^7 by a circuit which passes from the secondary of transformer G^4 , through wires 89 and 90, polar contact 91 of relay D^4 , wire 92, neutral contact 93 of relay D^4 , wire 94, primary of transformer J^7 , wire 95, polar contact 96 of relay D^4 , and wires 97 and 98 to the secondary of transformer G^4 . The secondary of transformer J^7 is connected across the rails of section 4-5 at the west end of this section. The polar contacts 91 and 96 of relay D^4 constitute a pole changer by virtue of which the current supplied to transformer J^7 is of normal or reverse relative polarity, according as relay D^4 is energized in normal or reverse direction.

Relay D^5 is, likewise, normally de-energized, but is controlled in such manner that when relay C^5 is de-energized relay D^5 is connected to the circuit of line relay H^4 in multiple with the latter relay. Relay D^5 , when energized, supplies track circuit train governing current to transformer J^8 , which transformer in turn supplies such current to the rails of section 4-5 at the right hand end of this section. The relative polarity of this current is controlled by the polar contacts of relay D^5 in the same manner as explained hereinbefore in connection with relay D^4 .

The line current element of the train governing energy system is furnished by transformers L , which in turn are supplied with current by transformers K , each of which is connected across the line wires 62 and 63 of the transmission line M , so that the line current is displaced in phase from track circuit current. Referring particularly to section 2-3, the circuit for the line

current for this section passes from secondary 99 of transformer L^3 , through wire 100, thence through the two halves of resistance 101 to the two rails of section 2—3, through these two rails in multiple to the two halves of resistance 102, and thence through wire 103 to secondary 99. In other words, alternating line current is constantly supplied to the rails of section 2—3 in multiple.

In a similar manner alternating line current is constantly supplied to the rails of section 3—4 by secondary 104 of transformer L^4 to the rails of section 4—5 by a secondary 105 of transformer L^4 , and to the rails of section 5—6 by secondary 106 of transformer L^5 .

The apparatus shown in the accompanying drawing is intended for co-operation with train-carried governing mechanism arranged to operate as follows:

When the train occupies a section of track which is supplied with line current and with track circuit train governing current of normal relative polarity, a proceed indication is given aboard the train; when the train occupies a section of track which is supplied with line current and with track circuit train governing current of reverse relative polarity, a caution indication is given aboard the train; and when the train occupies a section of track from which the supply of either line current or track circuit train governing current is discontinued, a stop indication is given aboard the train.

Assuming now that an eastbound train passes through the stretch of track shown in the drawing, it will be noted that as soon as such train enters section 2—3, it will receive track circuit train governing current from transformer J^6 . As the train enters section 3—4, it will de-energize track relay T^8 , thereby closing at contact 86 the circuit for transformer J^5 , so that the train will receive track circuit train governing energy from this transformer. The opening of track relay T^8 will also de-energize relay C^5 , which in turn will energize relay D^5 and this condition will be maintained as the train passes through section 4—5, so that while in the latter section the train will receive track circuit train governing energy from transformer J^8 . In section 5—6 the train will receive similar energy from transformer J^{12} which is controlled by apparatus to the east of the stretch shown in the drawing.

A westbound train entering section 5—6 will de-energize track relay T^5 , so that such train will receive track circuit train governing energy from transformer J^9 . The opening of track relay T^5 will de-energize relay C^4 , which in turn causes relay D^4 to become energized, and this condition will be maintained while the train passes through

section 4—5, so that while in the latter section the train will receive track circuit train governing energy from the transformer J^7 .

As the train passes through sections 3—4 and 2—3 it will receive track circuit train governing energy from transformers J^4 and J^3 , respectively.

While a westbound train is in section 5—6, the supply of track circuit train governing energy will be discontinued if signal S^5 is at stop, because under such conditions relay H^5 is de-energized, relay E^5 is accordingly de-energized, and the circuit for the primary of transformer J^9 is open at contact 108 of relay E^5 . While a westbound train is in section 4—5, the relative polarity of the track circuit train governing current supplied to such train is controlled by relay D^4 , which in turn is controlled by pole changer P^2 , so that if signal S^2 is at stop the energy supplied to the train will be of reverse relative polarity, thereby causing a caution indication on the train. In section 3—4 the relative polarity of the track circuit train governing energy supplied to a westbound train is determined by pole changing relay E^2 , so that if signal S^2 is at stop a caution indication will still be given aboard the train. When a westbound train is in section 2—3 a stop signal will be given aboard the train if signal S^2 is at stop, because at such time the circuit for transformer J^3 will be open at contact 71 of relay E^2 .

The control of the relative polarity of the track circuit train governing energy supplied to an eastbound train will be understood from the foregoing without further explanation.

One important feature of my invention is the control of the primary of transformer J^7 by auxiliary relay D^4 , which in turn is controlled by pole changer P^2 over a portion of the line circuit for relay H^5 . By means of this apparatus I am able to eliminate the necessity for an additional line wire through section 3—4 for the control of the primary of transformer J^7 . Similarly, by virtue of the control of transformer J^8 by relay D^5 , which in turn is controlled by a portion of the line circuit for relay H^4 , I am able to eliminate the necessity of an additional line wire through section 5—6.

Although I have herein shown and described only one form of apparatus embodying my invention, it is understood that various changes and modifications may be made therein within the scope of the appended claims without departing from the spirit and scope of my invention.

Having thus described my invention what I claim is:

1. In combination, a stretch of railway track provided with track circuits, two sig-

- nals governing traffic in one direction along said track, means for controlling the rear signal by the forward signal and by the intervening track circuits, normally inactive 5
 5 means controlled by a portion of the controlling means for the rear signal for supplying train governing energy to the track in advance of the rear signal, and means controlled by a train approaching said rear signal for rendering said last mentioned means active. 10
2. In combination, a portion of railway track over which traffic moves in both directions, an eastbound and a westbound signal for said portion, track circuits for said portion, a circuit for said westbound signal controlled by said track circuits and by traffic conditions to the west of said portion of track, an auxiliary relay, means controlled by said relay for supplying train governing energy to the track in advance of said westbound signal, and means controlled by a westbound train approaching said westbound signal for placing the eastbound signal at stop, and connecting said auxiliary relay with the circuit for said westbound signal. 15
 20
 25
3. In combination, a portion of railway track over which traffic moves in both directions, an eastbound and a westbound signal for said portion, track circuits for said portion, a polarized relay for said westbound signal, a circuit for said relay controlled by said track circuits and including a pole changer controlled by traffic conditions to the west of said portion of track, a second polarized relay, a third relay normally energized and operating when de-energized to place said eastbound signal at stop and to connect said second relay with the circuit for the first relay, means controlled by a westbound train approaching the westbound signal for de-energizing said third relay, means controlled by said second relay when thus connected with said circuit for supplying train governing energy to the track circuit immediately in advance of the westbound signal the polarity of such energy depending on traffic conditions to the west of said portion of track, and other means controlled by traffic conditions to the west of said portion of track for supplying train governing energy to the remaining track circuits in said portion. 30
 35
 40
 45
4. In combination, a portion of railway track provided with track circuits and with a signal, a circuit for said signal controlled by said track circuits and by traffic conditions beyond said portion of track, a normally de-energized relay operating when energized to supply train governing energy to a part of the track in advance of said signal, and means controlled by a train in the rear of said signal approaching the signal for connecting said relay with the circuit for said signal. 55
 60
5. In combination, a portion of railway track over which traffic moves in both directions, an eastbound and a westbound signal for said portion, track circuits for said portion, a polarized relay for said westbound signal, a circuit for said relay controlled by said track circuits and including a pole changer controlled by traffic conditions to the west of said portion of track, a second polarized relay, a third relay normally energized and operating when de-energized to place said eastbound signal at stop and to connect said second relay with the circuit for the first relay, means controlled by a westbound train approaching the westbound signal for de-energizing said third relay, means controlled by said second relay when thus connected with said circuit for supplying train governing energy to the track circuit immediately in advance of the westbound signal the polarity of such energy depending on traffic conditions to the west of said portion of track, and other means controlled by traffic conditions to the west of said portion of track for supplying train governing energy to the remaining track circuits in said portion. 65
 70
 75
 80
 85
6. In combination, a stretch of railway track provided with track circuits, two signals governing traffic in one direction along said track, means for controlling the rear signal by the forward signal and by the intervening track circuits, and means controlled in part by the said controlling means for such rear signal and set into operation by a train moving in said one direction approaching said rear signal for supplying train governing energy to a portion of the track in advance of the rear signal. 90
 95

In testimony whereof I affix my signature.

RONALD A. McCANN.
